UNITED STATES PATENT OFFICE.

ROBERT A. MORGAN, JR., OF BOSTON, MASSACHUSETTS.

COMBINED SUPPORT AND SAFETY DEVICE FOR OVERHEAD CONDUCTORS.

SPECIFICATION forming part of Letters Patent No. 417,497, dated December 17, 1889.

Application filed August 27, 1889. Serial No. 322,128. (No model.)

To all whom it may concern:

Be it known that I, ROBERT A. MORGAN, Jr., of Boston, county of Suffolk, State of Massachusetts, have invented an Improvement in a Combined Support and Safety Device for Overhead Conductors, of which the following description, in connection with the accompanying drawings, is a specification, like letters on the drawings representing like parts.

10 This invention relates to electric circuits in which an overhead wire or conductor forms one part of the circuit and the ground forms the other part thereof, and has for its object to provide the overhead conductor with preferably a number of safety devices, as will be described, whereby the current may be cut off from the ground in case the said wire becomes broken or is cut.

20 My invention is especially applicable to electric railways of that class in which the current is taken from a trolley-wire suspended above the car. As now commonly constructed and known to me, the trolley-wire forms one half of the electric circuit, the ground forming the other half, and if the trolley-wire becomes broken or is cut—as, for instance, in case of fire—the broken ends of the said wire might fall in contact with a person or animal and complete a short 25 circuit to the ground through the said person or animal, which might be attended with serious results.

It is the object of this invention to obviate liability of such accidents, and I accomplish 30 my object, as herein shown, by means of a combined trolley-wire support and safety device, which is rendered operative when the trolley-wire is cut or broken either to completely cut the trolley-wire out of circuit or 40 to shunt the current passing over the trolley-wire.

My invention therefore consists in the combination, with an overhead conductor forming part of a ground-circuit and made of independent sections, of a safety device or cut-out interposed between adjacent sections, whereby the current is cut off from the ground through a broken section, substantially as will be described.

50 Other features of my invention will be

pointed out in the claims at the end of this specification.

Figure 1 is a side elevation of a trolley-wire support and safety device embodying my invention, it being shown in its normal position to complete the circuit. Fig. 2 is a side elevation showing the trolley-support in position to cut off the current from the ground; Fig. 3, an under side view of the trolley-wire support shown in Fig. 1; Fig. 4, a transverse section of the trolley-wire support on line $x-x$, Fig. 1; Fig. 5, a transverse section on line $y-y$, Fig. 1; Fig. 6, a detail to be referred to; Figs. 7, 8, 9, and 10, details to be referred to; Figs. 11 and 12, modifications to be referred to; Figs. 13 and 14, details of modified forms of apparatus.

My improved support and safety device consists, as herein shown in Fig. 1, of two arms or sections $a-a'$, preferably provided with enlargements or disks a^2-a^3 , which are loosely mounted, as shown, on a sleeve a^4 of insulating material, into which is fitted a second sleeve a^5 , which may be of metal. The sleeve a^4 is provided with a collar a^6 , (see Fig. 4,) and the sleeve a^5 is also provided with a flange a^7 , between which and the collar a^6 is located a spiral spring a^8 . Each arm $a-a'$ and its disk a^2-a^3 is preferably made of metal, and the disks a^2-a^3 on their inner side are provided with insulation b , preferably pieces of hard rubber, secured to the disks on opposite sides of a central metallic or conducting portion 2, forming one contact member of the cut-out or safety device. The disks a^2-a^3 are mounted on the sleeve a^4 , so that their arms $a-a'$ extend in opposite directions, as shown in Figs. 1 and 2, and between the said disks may, and preferably will be, interposed an independent ring or disk b' , preferably of metal or other conducting material. The ring or disk b' is provided, as herein shown, on its opposite sides or faces with insulation b^2 , which may be pieces of hard rubber, mica, or other usual insulating material, it being shown in Fig. 7 as applied to the disk or ring b' on opposite sides of a central exposed or uncovered portion 3, forming the co-operating contact member of the support or safety device. The disks a^2-a^3 and inter-

mediate ring b' are secured on the sleeve a^5 , as shown in Fig. 4, by means of a nut b^4 , screwed upon the sleeve a^5 , a washer b^5 , of insulating material, being interposed between the said nut and disk a^3 , and the inner faces of the disks a^2 a^3 are kept in contact with the ring b' by the spring a^8 . The ring b' , as herein shown, has secured to it a threaded post c , upon which is placed a curved shield or guard c' , preferably of wood or insulating material, which is made of sufficient width to cover the disks a^2 a^3 and ring b' and protect them from rain, dirt, &c. The shield or guard c' is provided with an upright portion c^2 , having bent about it, as herein shown, one end of springs c^3 c^4 , extended out over the arms a a' , and having their outer ends fastened to shoes c^5 c^6 , adapted to slide upon the arms a a' . The springs c^3 c^4 are separated by washers c^7 , of insulating material, and covered by a guard c^8 , (shown as an inverted-trough-shaped bar,) the said guard being secured on the upright c^2 , as shown, by a washer c^9 and a nut c^{10} . The arms a a' have secured to them the trolley-wire d , which, as represented in Fig. 1, is made in sections, (marked 6 7,) the said sections being fastened to the arms a a' , as herein shown, by screws c^{12} . The trolley-wire support is suspended in the air by a span wire or rod d' , secured to posts d^2 at opposite sides of the roadway, and to avoid wear upon the parts of the support the sleeve a^5 is fitted upon a sleeve d^3 , having its opposite ends extended into a socket or recess in hubs d^4 , secured on the span-wire by set-screw d^5 . Each arm a a' is preferably made thicker, as at 5, (see Fig. 3,) to obviate heating of the metal arm at that point.

In operation the current normally passes from one section of the trolley-wire, as 6, to another section, as 7, through the arm a , contact members 2 3, and arm a' . If by accident or otherwise a section, as 7, of the trolley-wire becomes broken, cut, or otherwise disconnected, the said section of wire will face toward the ground, and the arm a' , being thus left unsupported, will be quickly turned by the spring c^4 from its horizontal position (shown in Fig. 1) to substantially the position shown in Fig. 2. As the arm a' drops down, the contact-member 2 of the disk a^3 is removed from contact with the member 3 of the ring b' and brought into contact with the insulation, thus breaking the circuit at this cut-out, so that if the loose trolley-wire section should come in contact with a person or animal, or, it may be, with combustible material, no injurious effects would result.

In order to prevent the arm a' from being raised again after it has fallen, I have provided a locking device for the said arm, it being herein shown as a projection d^{10} on each side or face of the ring b' , which co-operates with a depression or recess d^{12} (see Fig. 8) in each disk a^2 a^3 . The projection d^{10} may be made as a flat metal spring, or it may be formed by upsetting a part of the insulation.

When the wire is cut or becomes broken, the recess d^{12} on the disk a^3 is brought into line with the projection d^{10} and the latter springs 70 into the said recess. The fallen arm is thus locked and cannot be again raised to complete the circuit until the spring projection is positively unlocked.

I have shown and described my safety device as constructed so as to cut out the circuit; but I do not desire to limit myself in this respect, as the said device may be employed to cut out the broken wire from the ground and yet shunt the circuit around the 80 break in the wire. To accomplish this result, each disk a^2 a^3 may have secured to or forming part of it an additional strip or piece of metal o , situated substantially at right angles to the conducting-strip 2, so that when the 85 said disk is partially revolved at the breaking of the wire the strip or metal piece o is brought in contact with the contact member 3 of the ring b' , as indicated by dotted lines, Fig. 13. The metal strip o may be joined by 90 a flexible connection, as a wire o' , to a conductor o^2 , which is herein shown as carried down through the hollow post o^3 . The conductor o^2 may be connected with the ground, or it may be connected to a similar conductor 95 in an adjacent post.

I have herein described my invention as applied to trolley-wires; but it is evident it may be used equally well as a support for heavy power-wires forming part of a ground-circuit. So, also, I do not desire to limit my invention to the particular construction shown, as it may be variously modified to adapt it to different constructions, and while I may prefer to employ the ring b' , it is evident the said ring may be omitted and the two disks a^2 a^3 brought in contact with each other.

I have herein described the disks a^2 a^3 as made of metal and provided with insulation b ; but it is evident that the said disks may be made of insulating material and provided with metal strips to form contact-surfaces.

I have herein shown springs c^3 c^4 to move the arms a a' quickly when the wire is broken, 115 so that the circuit will be broken at the cut-out or safety before it is completed by the broken section of wire coming in contact with the ground; but I do not desire to limit myself to the use of springs, as it is evident the 120 arms a a' may be weighted at their outer ends.

I prefer to construct the cut-out or safety device substantially as shown in Fig. 1; but I do not desire to limit myself to this form of cut-out, as it may be made in other ways— 125 for instance, as shown in Fig. 11, wherein a rack-bar h is provided with collars h' at its opposite ends, located in boxes or cylinders h^2 h^3 , the said collars being acted upon by a normally-compressed spring h^4 . The opposite 130 ends of the rack-bar h are extended out through the boxes h^2 h^3 and have secured to them the ends of adjacent sections of the trolley or overhead wire. The rack-bar h

meshes with and rotates a disk h^6 , having a toothed periphery, and the disk h^6 may be provided with a contact-surface which co-operates with a like contact-surface on a like disk h^7 , firmly supported by arms h^8 , secured to the bar h^9 , connecting the boxes h^3 h^3 , the disk h^7 being also provided with a toothed periphery meshing with a rack-bar similar to the rack-bar h , and not herein shown.

10 The operation of the device is as follows, viz: As soon as a section of wire is broken the spring h^4 moves the rack-bar and rotates the disk h^6 sufficient to break the circuit, as above described.

15 I claim—

1. The combination, with an overhead conductor forming part of a ground-circuit and made of independent sections, of a safety device or cut-out interposed between adjacent 20 sections, whereby the current is cut off from the ground through a broken section, substantially as described.

2. The combination, with an overhead conductor forming part of a ground-circuit, of a 25 combined support and safety device consisting of two arms or sections provided with contact-surfaces, the said arms being movable one with relation to the other, whereby the said contact-surfaces may be disconnected when the overhead conductor is broken, and 30 substantially as and for the purpose specified.

3. The combination, with a span-wire d' ,

of a combined support and safety device consisting of arms pivotally supported by said wire and provided with contact-surfaces, and 35 a trolley-wire composed of sections, as 6 7, secured to said arms, substantially as described.

4. The combination, with an overhead conductor forming part of a ground-circuit, of a combined support and safety device consisting of two arms or sections provided with contact-surfaces, the said arms being movable one with relation to the other, whereby the said contact-surfaces may be disconnected when the overhead conductor is broken, and a locking device for said arms, substantially as described.

5. The combination, with an overhead conductor forming part of a ground-circuit, of a combined support and safety device consisting of two arms or sections provided with contact-surfaces, the said arms being movable one with relation to the other, whereby the said contact-surfaces may be disconnected when the overhead conductor is broken, and 50 springs to act on said arms, substantially as and for the purpose specified.

In testimony whereof I have signed my name to this specification in the presence of two subscribing witnesses.
